UNITED STATES PATENT OFFICE.

PETER P. WELTY, OF PANDORA, OHIO.

LATCH FOR SLIDING DOORS.

Application filed February 17, 1928. Serial No. 255,077.

This invention relates to improvements in latches for sliding doors, one object of the invention being the provision of a device of this character which is especially designed 5 for use upon garage and barn doors and which is of a type that is provided with a latching member actuated during the rotation of the carrying member to be moved toward and within the door during the 10 unlatching action and to be moved away from and into latch-engaging position when the door is closed and being latched.

Another object of this invention is the provision of a device of this character which 15 can be made universal, that is, so that it can be operated right- or left-handed, and which is easily assembled and put into operation upon the present type of garage and barn doors.

20 In the accompanying drawings:—

Figure 1 is a horizontal section through the door frame and a door with the present device in the position it assumes when latched, the said device being viewed from 25 above;

Figure 2 is a front elevation or view taken from the outer side of the door with the device latched;

Figure 3 is a view similar to Figure 1 with 30 the device in unlatched position;

Figure 4 is a detail view of the latch-engaging member; and

Figure 5 is a plan view of the double cam plate.

35 Referring to the drawings, the numeral 7 designates the door frame or post and 8 the door, said door being provided with the batten 8' which, as will presently appear, provides a receptacle for the present device when 40 in unlatched position.

Attached to the outer face of the door is a plate 9 which is provided with the sleeve or cylindrical boss 10 which is adapted to be seated in the door 8 and be attached thereto 45 by means of the screws 11. A stem 12 is mounted in the member 10 for both rotary and longitudinal movement, the same being provided with the operating handle 13 which is disposed upon the plate side and having an 50 apertured terminal end 14, the purpose of which will presently appear. Detachably connected to the inner end of the stem 12 is the double latch member 15, the same being so constructed that the set screw 16 may 55 fasten the same in position to be operated either as a right-hand or as a left-hand de-

vice, that is, as illustrated, the device is a left-hand latch due to the fact that the handle 13 is in the left-hand position, but if it were to be operated as a right-hand latch, it would be 60 moved to a position at 180° from the point as illustrated, and the latch member 15 would be released and latched so as to assume the same position as that in which it now appears, except that its engaging coacting member 65 would be disposed to engage the hook terminal 17' instead of the terminal 17, as now illustrated.

A spring 18 surrounds the stem 12 and abuts the bushing 10 and the latch member 70 15 so as to normally hold the same in the position as shown in Figure 1 with the arm 13 riding in the lowermost portion of the plate 9. This plate 9, as shown, is provided with the two inclined cam raised portions 19 and 19' so that when the lever 13 is moved upwardly and to the right, as viewed in Figure 2, the same will ride upon the cam surface 19, and during such movement, the stem 12 will be rotated and also moved longitudinally downwardly, as viewed in Figure 1, so 80 as to elevate the hook 17 and draw the member 15 from the position, as shown in Figure 1, to that shown in Figure 3, so as to be housed within the space formed by the batten 8'. The lug 20 is provided intermediately of 85 the two cammed surfaces 19 and 19' and acts as a limiting means for the extreme right-hand position of the lever 13, or when the device is used as a right-hand device to limit 90 it in its extreme left-hand movement.

The coacting hook-receiving or latch plate 21 is attached by screws 22 to the inner face of the frame 7 so that its apertured abutment 23 is disposed to be engaged by either one of the hooks 17 or 17', here shown as being engaged by a hook 17 when the door is latched and the parts assume the position as shown in Figure 1. It will be noted that this member 21 is so shaped as to be placed upon the right-hand frame of the door when the device is 100 operated as a right-hand latching device.

Attached to the outer face of the door and in the path of the outer end of the lever 13 is a plate 24 the screws 25 being provided for 105 securing the same and for holding the plate so that the upstanding lug 26 will be in the path to receive the apertured terminal 14 of the lever 13 so that a padlock (not shown) may be inserted in the opening 27 thereof to 110 lock the lever against upward displacement.

From the foregoing description, it is evi-

dent that with a device of this character a proper latching device is provided for sliding barn and garage doors and one in which when the lever 13 is moved in one direction the 5 latch member 15 is rotated so as to disengage one of its hook terminals from the plate 21, and after such disengagement, the action of the cams 19 and 19' will cause the stem 12 to be operated against the spring 18 so that the 10 member 15 is seated within the outer face of the batten 18' and thus in a position where it will not protrude and provide an abutment that will be in the way when the door is slid in the desired direction for opening and closing. It is also evident that when the lever is moved in the opposite direction, the member 15 will be moved both longitudinally and 15 rotatively so that the hook terminals 17, 17' will be brought into latching position, as 20 shown in Figure 1.

It is also evident that the latch can be operated from the inside, and that the complete device can be used on swinging as well as sliding doors, the metal parts being made 25 of any desirable metal.

I claim:—

1. The combination with a door frame and a door, said door being provided with a recess upon the face side thereof, of a latch 30 device therefor including a member carried by the door and capable of rotary and longitudinal movement, a latch member carried upon the inner end of the same and adapted when in latching relation to be projected beyond and out of the recess, and when in released position to be seated within the recess, means attached to the frame for engaging the latter when external of the recess, and means externally of the door for operating the rotary member.

2. The combination with a door frame and a door, said door being provided with a recess upon the frame side thereof, of a latch device therefor including a member carried 45 by the door and capable of rotary and longitudinal movement, a latch member carried upon the inner end of the same and adapted when in latching relation to be projected beyond and out of the recess, and when in released position to be seated within the recess, means attached to the frame for engaging the latter when external of the recess, means externally of the door for operating the rotary member, and a spring for normally holding the latter member extended.

3. The combination with a door frame and a door, said door being provided with a recess upon the frame side thereof, of a latch device therefor including a member carried 60 by the door and capable of rotary and longitudinal movement, a latch member carried upon the inner end of the same and adapted when in latching relation to be projected beyond and out of the recess, and when in re-

leased position to be seated within the recess, 65 means attached to the frame for engaging the latter when external of the recess, means externally of the door for operating the rotary member, a spring for normally holding the latter member extended, and cooperating 70 means carried by the rotary member and in the path thereof to impart longitudinal movement to the rotary member during the rotation of the same.

4. A latch for sliding doors, including a 75 plate having a cammed surface upon the outer face thereof and provided with a concentric aperture, a substantially L-shaped member, one terminal of which forms the stem and which is mounted for longitudinal sliding 80 and rotary movement in the aperture of the plate, the opposite terminal being disposed to engage the cam to impart sliding movement to the stem during the rotation of the stem, a spring mounted upon the stem and 85 normally holding the operating terminal toward the cam, and a right-angled latching member carried upon the free end of the stem.

5. A latch for sliding doors, including a 90 plate having a cammed surface upon the outer face thereof and provided with a concentric aperture, a substantially L-shaped member, one terminal of which forms the stem and which is mounted for longitudinal sliding 95 and rotary movement in the aperture of the plate, the opposite terminal being disposed to engage the cam to impart sliding movement to the stem during the rotation of the stem, a spring mounted upon the stem and 100 normally holding the operating terminal toward the cam, a right-angled latching member carried upon the free end of the stem, and means carried by the plate for limiting the rotary movement of the stem.

6. A latch for sliding doors, including a 105 plate having a cammed surface upon the outer face thereof and provided with a concentric aperture, a substantially L-shaped member, one terminal of which forms the stem and which is mounted for longitudinal sliding 110 and rotary movement in the aperture of the plate, the opposite terminal being disposed to engage the cam to impart sliding movement to the stem during the rotation of the stem, a spring mounted upon the stem and normally holding the operating terminal toward the cam, a right-angled latching member carried 115 upon the free end of the stem, means carried by the plate for limiting the rotary movement of the stem, the operating end of the stem being apertured, and a padlock-receiving member disposed in fixed relation thereto for receiving the same when the stem is in latched position.

In testimony whereof I have hereunto set 125 my hand.

PETER P. WELTY.
